UNITED STATES PATENT OFFICE.

HARMON GIEBEL, OF NEW YORK, N. Y.

DESIGN FOR A DECORATIVE FABRIC.

SPECIFICATION forming part of Design No. 32,522, dated April 10, 1900.

Application filed March 15, 1900. Serial No. 8,846. Term of patent 14 years.

To all whom it may concern:

Be it known that I, HARMON GIEBEL, a citizen of the United States, residing in the city of New York, borough of Brooklyn, in the county of Kings and State of New York, have invented and produced a new and original Design for Decorative Fabrics, of which the following is a specification, reference being had to the accompanying drawing, forming a part thereof.

In the accompanying drawing the figure represents the front view of my new design, which consists, essentially, of an elongated horizontal panel A, bearing the representation of a series of loops or festoons *a a*, pendent from

its upper edge, said loops or festoons *a a* having interposed between them the folds or gatherings *f f*, hanging from the points at which the loops or festoons *a a* are represented as being gathered together.

Having now described my invention, what I claim as new, and desire to secure by Letters Patent, is—

The design for a decorative fabric, as herein shown and described.

HARMON GIEBEL.
